(57) CLAIM

The ornamental design for a sandal upper, as shown and described.

DESCRIPTION

FIG. 1 is a perspective view of a sandal upper showing my new design;

FIG. 2 is a top view thereof;

FIG. 3 is a left side view thereof;

FIG. 4 is a front view thereof;

FIG. 5 is a right side view thereof;

FIG. 6 is a rear view thereof; and,

FIG. 7 is a perspective view thereof, showing the ankle straps tied in a bow.

The broken line outlines of the footwear sole illustrate environment and form no part of the claimed design. The straps of the sandal upper are illustrated with symbolic breaks. The appearance of any portion of the article between the symbolic break lines forms no part of the claimed design.

1 Claim, 7 Drawing Sheets
